Specification for Design.

Patented Nov. 30, 1920.

Application filed April 10, 1920. Serial No. 373,024. Term of patent 14 years.

To all whom it may concern:

Be it known that I, JOHN H. DAVIDSON, a citizen of the United States, residing at Orono, in the county of Penobscot and State of Maine, have invented a new, original, and ornamental Design for a Badge, Especially Intended for Members of the American Legion, of which the following is a specification, reference being had to the accompanying drawing, forming a part thereof.

The figure is a plan view of the badge showing my new design.

I claim—

The ornamental design for a badge as shown.

JOHN H. DAVIDSON.
